UNITED STATES PATENT OFFICE

2,600,907

SINGLE FACER DRIVE

Elmer L. Mumma, Glen Arm, Md., assignor to
 F. X. Hooper Company, Inc., Glen Arm, Md., a
 corporation of Maryland

Application October 4, 1947; Serial No. 777,963

8 Claims. (Cl. 154—31)

1

This invention relates to an improvement on a single facer corrugating machine. The usual single facer corrugating machine has two corrugating rolls one of which is power driven and the other of which is driven from the driven roll through means of the corrugations on both the rolls. Also such machines have a presser roll which carries the liner into contact with the fluted strip, which has previously had adhesive applied to the projections thereof, so that the presser roll presses the liner against these projections so that the two strips thereafter adhere together. The presser roll is usually driven through means of gears on it and on the adjacent driven corrugating roll. For a given thickness of stock the diameters of the corrugating roll and the adjacent presser roll can be so designed that this gear drive between them works perfectly. However, it is known that the stock varies in thickness and for this reason the presser roll had been made adjustable to and from the corrugating roll. No provision has been made to change the relative speeds of the two rolls because of this variation in thickness of stock. The fluted strip and liner are pressed so firmly between the driven corrugating roll and the presser roll that the surfaces of these two rolls are virtually driven one from the other and when stock of a different thickness than that for which the diameters of the rolls and the initial gearing are designed is used on the machine the tendency is for the driven corrugating roll, through the stock, to drive the presser roll at a different speed than the speed that the gearing is designed to drive it. This causes a wearing of the gearing and a slippage and a corresponding imperfection in the stock or board produced on the machine.

In the instant invention the presser roll is driven from an independent motor from that driving the corrugating roll and yet the motors driving the respective rolls are so interconnected that when the speed of the larger motor driving the corrugating roll is changed, the speed of the smaller motor driving the presser roll will correspondingly be changed.

The invention also contemplates means for changing the speed of the presser roll driving motor independently of the motor driving the corrugating roll.

Other objects and advantages of the invention will be apparent from the following description and the accompanying drawings forming a part hereof, and in which:

Figure 1 is a side elevational view of a single

2

facer corrugating machine embodying the improvements of this invention.

Figure 2 is a fragmentary view of the various driving mechanisms employed.

Figure 3 is a side elevation of the separate driving motor for the presser roll.

Figure 4 is a fragmentary end elevation showing the presser roll and the corrugating roll as they come together to permanently attach the liner to the fluted strip.

Figure 5 is a diagrammatic view of the driving mechanism and circuit.

Figure 6 is a fragmentary view of a possible modification of this driving mechanism.

15 In the drawings similar numerals refer to similar parts throughout the several views.

The single facer corrugating machine shown has upper and lower corrugating rolls 1 and 2 respectively with grooves thereon which form the flutes in the strip 3 as it is drawn therethrough. An adhesive applying mechanism 4 applies adhesive to the projections of the flutes of roll 2. A liner 5 is brought up to the fluted strip through means of a series of rolls terminating in presser roll 6. Presser roll 6 may be adjusted to or from corrugating roll 2 through means of the eccentric 7 and screw 8. The precise operation of this mechanism, forming no part of the present invention is shown in Patent No. 2,106,500, January 25, 1938.

20 Lower corrugating roll 2 is driven through means of a motor 9 and gear reduction mechanism 10. Instead of driving the presser roll 6 from gears on roll 6 and roll 2, roll 6 is driven through a small separate motor 11. The rolls are driven through means of gears and chains from their respective motors.

25 Power is introduced to the corrugating unit through means of an alternating current fed to alternating current motor 12, the rotor of which is on the same shaft as the rotor of direct current generator 13, so that the motor operates the generator whenever the motor is operating, and through means of belt 14 driven from the same motor-generator shaft, exciter 15 is driven. Current from the exciter energizes the fields of motors 9 and 11. Current from the D. C. generator 13 energizes the rotors or armatures of the motors 9 and 11. A rheostat 16 in the field of 30 the D. C. generator 13 may be used to vary the supply of current to the armatures of the motors 9 and 11 and thereby simultaneously vary their speed.

If desired a further rheostat 17 may be used in the field of the small motor 11 to independently

vary its speed. Various control mechanisms in the circuit of the exciter are generally indicated at 18 and this mechanism is all old and forms no part of the instant invention.

From Figure 1 it will be apparent that as the strip 3 on roll 2 having had its corrugations made therein by means of rolls 1 and 2, and having had adhesive applied to the outer tips, as it comes into contact with liner 5 on roll 6 will tend to drive roll 6 from roll 2, if the diameters of the respective rolls and the initial setting of the respective drives is not exactly correct for the thickness of the two strips being used. Of course the more powerful drive imparted to roll 2 will tend to drive or hold back the weaker drive of roll 6. Since both large motor 9 and small motor 11 are driven from the same current it will be apparent that changing that current will change their speeds proportionately so that the machine can put out the number of feet per minute required simply by changing the rheostat 13. However, for a different total thickness of stock in the strips 3 and 5, different relative speeds of the rolls 2 and 6 would be preferred. However, since small motor 11 takes its current from the same circuit as large motor 9, if motor 11 is slowed down because of the surface drive of roll 6 at a lower rate of speed, no harm will result to the circuit or the motor 11. If on the other hand, because of the surface speeds of the two rolls, roll 6 is driven faster than the original design intended so that small motor 11 is correspondingly driven faster, then small motor 11, being a D. C. motor will simply act as a generator and generate more power for the circuit and therefore for the large motor 9 and possibly even tend to increase the speed of large motor 9. Of course this increase of speed could readily be slowed down, if not desired, by means of rheostat 13.

If on the other hand, an accurate adjustment of the speed of the small motor 11 should be desired for every variation of thickness of stock, the rheostat 17 could be used to independently adjust the speed of small D. C. motor 11.

There is thus shown a drive for the presser roll which is independent of the drive of the corrugating machine proper and which yet may be adjusted in speed in unison with the large motor of the corrugator, because of taking current from the same D. C. generator, and yet the small motor may itself be adjusted in speed independently of the speed of the large motor driving the machine.

With this structure there is no tendency of the surface speeds of the presser roll and adjacent corrugating roll working injuriously against the drive of the presser roll and also there is a complete avoidance of injury to the board made on the machine because of this flexibility of the drive of the presser roll, which is substantially complete.

It will be apparent that many modifications may be made in the drive of the presser roll and the other features disclosed without departing from the invention.

What is claimed as new and is desired to be secured by Letters Patent is:

1. In a corrugating machine having a pair of adjacent corrugating rolls adapted to flute stock strip passing therebetween, and a liner strip applying presser roll immediately adjacent one corrugating roll to apply a liner strip to one face of the fluted stock strip on the adjacent corrugating roll, the corrugated stock strip and liner strip

each passing around a substantial proportion of the circumferences of the said one corrugating roll and presser roll respectively and then tightly between said rolls, whereby one of said rolls tends to be driven by the other and means to apply adhesive to the face of one of said strips facing the other said strip prior to their passage between said one corrugating roll and the presser roll, separate motors to drive said one corrugating roll and said presser roll, means interconnecting the power supply for said motors and means for simultaneously varying the speeds of said motors to vary to the same extent the speed of said one corrugating roll and said presser roll, both said driving motors operating on the rolls in addition to the rotary effect caused by the passage of the strips between the adjacent corrugating and presser rolls.

2. In a corrugating machine having a pair of adjacent corrugating rolls adapted to flute stock strip passing therebetween, and a liner strip applying presser roll immediately adjacent one corrugating roll to apply a liner strip to one face of the fluted stock strip on the adjacent corrugating roll, the corrugated stock strip and liner strip each passing around a substantial proportion of the circumferences of the said one corrugating roll and presser roll respectively, and then tightly between said rolls, whereby one of said rolls tends to be driven by the other and means to apply adhesive to the face of one of said strips facing the other said strip prior to their passage between said one corrugating roll and the presser roll, separate motors to drive said one corrugating roll and said presser roll, means interconnecting the power supply for said motors and means for simultaneously varying the speeds of said motors to vary to the same extent the speed of said one corrugating roll and said presser roll, and means including said adjacent rolls and strips, when the machine is in operation, to vary the power applied to one of said motors upon a variation in the speed of the other motor.

3. The corrugating machine of claim 2 including means independent of the driving motor for the corrugating roll to vary the speed of the presser roll driving motor.

4. In a corrugating machine having a pair of adjacent corrugating rolls adapted to flute stock strip passing therebetween, and a liner strip applying presser roll immediately adjacent one corrugating roll to apply a liner strip to one face of the fluted stock strip on the adjacent corrugating roll, the corrugated stock strip and liner strip each passing around a substantial proportion of the circumferences of the said one corrugating roll and presser roll respectively, and then tightly between said rolls, whereby one of said rolls tends to be driven by the other and means to apply adhesive to the face of one of said strips facing the other said strip prior to their passage between said one corrugating roll and the presser roll, an electric motor to drive said one corrugating roll, a separate electric motor to drive the presser roll, circuit means connecting said motors and a rheostat in said circuit to vary the speeds of the two motors in unison.

5. In a corrugating machine having a pair of adjacent corrugating rolls adapted to flute stock strip passing therebetween, and a liner strip applying presser roll immediately adjacent one corrugating roll to apply a liner strip to one face of the fluted stock strip on the adjacent corrugating roll, the corrugated stock strip and liner strip

each passing around a substantial proportion of the circumferences of the said one corrugating roll and presser roll respectively, and then tightly between said rolls, whereby one of said rolls tends to be driven by the other and means to apply adhesive to the face of one of said strips facing the other said strip prior to their passage between said one corrugating roll and the presser roll, two separate variable speed motors, one for driving said one corrugating roll and the other for driving said presser roll, means for simultaneously starting said motors, and means for simultaneously varying the speeds of said motors to maintain the same peripheral speeds of the presser roll and the adjacent corrugator roll.

6. In a corrugating machine having a pair of adjacent corrugating rolls adapted to flute stock strip passing therebetween, and a liner strip applying presser roll immediately adjacent one corrugating roll to apply a liner to one face of the fluted stock strip on the adjacent corrugating roll, the corrugated stock strip and liner strip each passing around a substantial proportion of the circumferences of the said one corrugating roll and presser roll respectively, and then tightly between said rolls, whereby one of said rolls tends to be driven by the other and means to apply adhesive to the face of one of said strips facing the other said strip prior to their passage between said one corrugating roll and the presser

roll, separate motors to drive said one corrugating roll and said presser roll, the motor driving the presser roll being substantially smaller than the motor driving the said presser roll and yielding to the drive of the presser roll in the event of a difference in the surface speeds of the two separate motor driven rolls when in operation.

7. The corrugating machine of claim 6 including means to vary the speed in unison of said two driving motors for both said rolls.

8. The corrugating machine of claim 6 including means to vary the speed of the presser roll driving motor independently of the speed of the corrugating roll driving motor.
